GEORGE B. DAMON
BY *Attn: Mr. and Mrs. Damon*
ATTORNEYS

UNITED STATES PATENT OFFICE.

GEORGE B. DAMON, OF BELVIDERE, NEW JERSEY, ASSIGNOR TO VULCAN IRON WORKS, OF WILKES-BARRE, PENNSYLVANIA, A CORPORATION OF PENNSYLVANIA.

DRIER.

Application filed July 17, 1920. Serial No. 397,055.

To all whom it may concern:

Be it known that I, GEORGE B. DAMON, a citizen of the United States of America, residing at Belvidere, in the county of Warren and State of New Jersey, have invented certain new and useful Improvements in Driers, of which the following is a specification.

My invention relates to driers, and particularly to driers of the double shell rotating type of construction. Among the objects of my invention may be specially mentioned (a) to afford an increased supply of heated gases to the drier and particularly 10 to the annular space through which the material under treatment passes; (b) to control the quantity and the temperature of the gases passing through the inner shell and independently of the quantity and temperature 15 of the gases passing through the annular drying chamber; (c) to pass the gases through the drier in such direct fashion that the ordinary suction fan may be dispensed with and be replaced by an ordinary stack; (d) to provide heat storage 20 means through which the gases pass to the drier, thus to maintain substantially uniform the predetermined temperature conditions; (e) to provide means for breaking up 25 the stratification of the gases passing to the drier—(this means may be the same as that just mentioned); (f) to provide more room 30 at the feed end of the drier for the introduction of the material to be treated. Other 35 features of improvement will be hereinafter pointed out or illustrated in the accompanying drawings, in which—

Fig. 1 is a broken side elevation of a drier in which my invention is embodied in one 40 form;

Figs. 2 and 3 are sections on the lines II—II and III—III, Fig. 1, respectively; and

Fig. 4 is a diagram of an alternative construction.

It is of course premised that the details of the construction shown may be varied in many ways while nevertheless embodying what I claim as my invention; and it is to 50 be understood that the drawing shows but an illustrative embodiment of that invention.

The material enters the drier at a feed hopper 5 of any suitable type, and passes to

the annular drying chamber afforded between the outer cylinder 6 and the inner shell or flue 7. The cylinder is arranged on an incline and rests on rollers 8 through bearing rings 9 of usual type, so that as it is rotated by spur gear 10, driven through bevel wheels 11 and 12, and meshing with the gear ring 13 on the cylinder, the material passes gradually through the cylinder and discharges through chute 14 to a trough-like hopper 15, in which is arranged a screw conveyor 16, or other means for removing the material from the drier. The flue 7 is supported from the outer shell by spiders 17, which, as shown at 18, may be of flexible link type to permit relative longitudinal displacement of the parts incident to longitudinal expansion or contraction at the temperatures to which they are subjected. As shown in Fig. 1, the flue is conical, with its small end arranged toward the discharge end 75 of the cylinder. This arrangement may be reversed, as indicated diagrammatically in Fig. 4. In any event, both inner and outer shells carry longitudinally extending flights 19 which project into the drying chamber 80 and serve to cascade the material as it passes through the drying chamber during the rotation of the cylinder.

The heated gases which are led through the drier comprise, in part, the products of combustion from the fire chamber 20. These pass from the fire chamber to a tempering chamber 21, thence through checkerwork 22 to a second tempering chamber 23 (into which the intake of the flue 7 opens), thence 90 through a second checkerwork 24 to a third tempering chamber 25, to which cylinder 6 opens. The gases pass through both the flue 7 and the annular chamber between the latter and the cylinder 6 to the stack 26. 95 To each of the tempering chambers 21, 23 and 25 open ports 27 controlled by slide valves 28. Thus the hot products of combustion from the fire chamber are tempered by the admission of excess air (i. e., air 100 supplemental to that admitted to the fire box in which complete combustion takes place) in chamber 21 to a temperature suitable for the inlet to the flue 7 of the drier. It passes to this flue through the checkerwork 22, which not only mingles the ancillary air with the products of combustion, but also stores up this heat and imparts it

to the gases, should the latter fall below desired temperature by reason of a low fire in the chamber 20. In chamber 23 the gases are further tempered by the admission of 5 more air and pass through checkerwork 24 (having the same function as 22) to chamber 25, where a further and final admission of air occurs before they pass into the annular space between the inner and outer 10 shells.

The value of the present construction will be recognized from the following consideration. The amount of vapor which a space can carry is controlled by and rapidly increases with the temperature. It is therefore economy to operate the drier at relatively high (say 180-200° F.) discharge temperature. On the other hand certain materials passing through the drier can be 15 subjected without injury to higher temperature than others. Thus, for drying iron ores the temperature of the flue may be as high as 1000° F., while for drying coal a temperature this high cannot be used with 20 safety. The flexibility of temperature control by the valved ports 27 is therefore important—as well as the maintenance of a uniform temperature by the checkerwork grids through which the gases pass to the 25 drier.

The construction of the conical flue as shown in Fig. 1, that is to say with its apex at the discharge end of the cylinder, is of value in drying such materials as give 30 off their moisture readily—such, for instance, as wet sand. The conical shape of the flue accelerates the passage of the material through the drier.

On the contrary, when the material is of 40 such character that it is slow to give off its moisture—as for instance coal, loam, clay, some iron ores, limonite, etc.—the reverse arrangement of the flue illustrated in Fig. 4 is preferable, since this construction retards the passage of the material through 45 the drier. Furthermore, the gases passing through the flue contract as they cool, and the construction accommodates this condition. Again, it affords increased room at 50 the end of the drier to which the material is fed and permits the use of mechanical feeders, which may be required for feeding plastic materials, such as clay, etc. Again, by reason of its retarded travel through the 55 flue, the material is retained for the longest period in contact with the hottest portion of the shell, viz, the fire-box end, and this is what is needed for materials that are loath to part with their moisture. The gases 60 entering the annular drying chamber are hottest at the fire-box end, and in the best condition to evaporate the least vestige of moisture in the material: briefly, the hottest gas strikes the driest material. Moreover, 65 by providing a damper X at the stack end

of the flue 7, the temperature of the latter can be maintained at a predetermined elevation.

By reason of the direct travel of the gases through the drier, the customary exhaust 70 fan may be dispensed with, although the use of a fan F, when needed, is contemplated. The velocity of the gases passing through the annular drying chamber can be so regulated by a damper D in, and the height 75 of, the chimney, and by the forced draft in the ashpit, that a condition of "balanced draft" can be created. That is to say, the pull of the stack (or of the fan, when used) may be so regulated as to carry off the 80 products of combustion from the fire chamber, plus the ancillary air admitted through the ports 27 and passing through the flue 7 and the annular space between the latter and the shell 6, together with the moisture 85 taken up from the material passing through the drier. Furthermore, this regulation may be so accurate that the gases emerging from the annular chamber are just below the point of moisture saturation. The value of such 90 an arrangement is obvious.

The details of construction may be varied in many ways and for different materials under treatment. The constructions shown and described constitute but an illustrative 95 embodiment of what I claim as my invention.

I claim—

1. A drier comprising a rotary shell and inner flue affording between them an annular drying chamber of gradually increasing area from one end to the other, and having its bottom inclined in one direction, gas inlets and outlets at opposite ends of the drier, means for feeding material to the 100 annular chamber at the gas outlet end thereof, and means for receiving said material as discharged at the gas inlet end of said chamber.

2. A drier comprising a rotary shell and inner flue affording between them an annular drying chamber of gradually increasing area from one end to the other, and having its bottom inclined in one direction, gas inlets and outlets at opposite ends of the drier, means for feeding material to the 105 annular chamber at the gas outlet end thereof, and means for receiving said material as discharged at the gas inlet end of said chamber, together with means for admitting hot gases at different temperatures 110 respectively to said flue and annular drying chamber.

3. The combination with a rotary drier having an outer shell and inner flue affording between them an annular drying chamber, of a source of supply of heated gases and an intake for the flue closer to the said source than the intake for the drying 115 chamber.

4. The combination with a rotary drier having an outer shell and an inner flue affording between them an annular drying chamber, of a fire chamber and tempering chambers interposed between the same and the drier, the intake for the drying chamber being arranged in a tempering chamber more remote from the fire chamber than that for the intake of the flue.
5. The combination with a rotary drier, of a fire chamber for supplying heated gases thereto, and tempering chambers arranged in extension of the drier and interposed between the fire chamber and the intake for the drier.
6. The combination with a rotary drier, of a fire chamber for supplying heated gases to the drier, a group of heat storage elements through which the products of combustion pass to the drier to equalize the temperature of the gases supplied thereto under varying fire conditions, said heat storage elements being arranged in series, together with means for admitting gases to the drier from different points in said heat storage series.
7. The combination with a rotary drier of a fire chamber, checkerwork partitions interposed between the fire chamber and the drier, and intakes to the drier opening to the areas between different partitions, for the purpose described.
8. The combination with a rotary drier, of a fire chamber, a checkerwork partition interposed between the fire chamber and the drier, and excess air inlets opening to the fire-box side of said partition to temper the gases from the fire chamber, said checkerwork serving to mingle the ancillary air and gases from the fire chamber.
9. The combination with a rotary drier having an outer shell and inner flue, of a fire chamber for supplying heated gases to the drier, a checkerwork through which the gases pass to the annular drying chamber between the shell and flue, the intake of the latter extending through said checker work.
10. The combination with a rotary drier having an outer shell and inner flue, of a fire chamber for supplying heated gases to the drier, a checkerwork through which the gases pass to the annular drying chamber between the shell and flue, the intake of the latter extending through said checkerwork, together with ports admitting excess air to gases from the fire chamber which enter the drying chamber.
11. In a rotary drier, the combination with a rotary shell and inner flue affording an annular drying chamber, a stack to which said chamber and flue admit the gases passing therethrough, means for feeding material to the chamber at the stack end thereof, a fire box at the opposite end of the drier, and independent intakes therefrom to the flue and drying chamber respectively.
12. In a rotary drier, the combination with a rotary shell and inner flue affording an annular drying chamber, a stack to which said chamber and flue admit the gases passing therethrough, means for feeding material to the chamber at the stack end thereof, a fire box at the opposite end of the drier, and independent intakes therefrom to the flue and drying chamber respectively, the intake from the flue being arranged to receive hotter gases than those admitted to the drying chamber.
13. In a rotary drier, the combination with an outer shell and inner flue affording an annular drying chamber between the same, of means for flowing gases at different temperatures in the same direction through said flue and chamber.
14. In a rotary drier, the combination with an outer shell and inner flue affording an annular drying chamber between the same, of means for flowing gases at different temperatures in the same direction through said flue and chamber, together with a common stack to which said gases discharge.
15. The combination with a rotary drier, of a fire box, means for mingling excess air with the products of combustion therefrom, and means for breaking up the stratification of said excess air and products of combustion before they are admitted to the drier.
16. A drier comprising a rotary shell and an inner flue affording between them an annular drying chamber of gradually increasing area from one end to the other of the drier together with means for leading gases at different temperatures in the same direction through said flue and annular drying chamber.
- In testimony whereof I have signed my name to this specification.
- GEORGE B. DAMON.
